UNITED STATES PATENT OFFICE.

BIRNEY DYSART, OF CINCINNATI, OHIO.

ADDING-MACHINE.

1,282,058.

Specification of Letters Patent.

Patented Oct. 22, 1918.

Application filed May 25, 1917. Serial No. 170,863.

To all whom it may concern:

Be it known that I, BIRNEY DYSART, a citizen of the United States, residing at the city of Cincinnati, county of Hamilton, and State of Ohio, have invented a new and useful Adding-Machine, of which the following is a specification.

This invention relates to adding machines.

An object of the invention is to provide an adding machine having a series of adding pinions or wheels operable to receive and add the amounts by coöperation with the actuating racks, one of the racks being arranged to coöperate simultaneously with a plurality of orders in the differential mechanism and at one operation introduce into a single one of the adding pinions a number composed of a plurality of digits set up or registered in different numerical orders in the differential mechanism.

Another object of the invention is to provide an adding machine having a differential mechanism in which the digits of the numbers may be set up in different numerical orders according to the decimal system of notation, in which ten units of one order make one unit of the next higher order; and to provide such machine with equipment by which the numbers may be added and the sum thereof exhibited or recorded according to a different system of notation as, for instance, the duodecimal system in which twelve units of one order make one unit of the next higher order.

A further object of the invention is to provide an adding machine including differential mechanism capable of having set up therein a compound number in which there is a varying relative value between different columns or numerical orders, and in which machine a plurality of such compound numbers may be successively set up and added and the sum thereof exhibited according to such compound system of notation regardless of the fact that the number of units in some orders, according to such compound system of notation required to make one unit of the next higher order, may be greater than ten and not an even multiple thereof.

An additional object is to provide an adding machine of the character mentioned in which each digit when introduced or set up in the machine is represented by a stop in units numerical order and is automatically advanced progressively to the next higher order as an incident to the introduction or

setting up of each succeeding digit, the last digit introduced or set up remaining in units order and in which the highest digital value which can be introduced or registered in any given order is nine, and further in which the various numbers so introduced or set by successive operations may be added and the sum thereof exhibited according to a system of notation in which the number of units required to make one unit of the next higher order is more than ten.

Among the specific objects of the invention may be mentioned the adaptation and equipment of the well known Dalton adding machine which is manufactured in substantial conformity with the adding mechanism shown in Hubert Hopkins' Patent No. 1,039,130, dated September 24, 1912, with co-operating mechanism embodied in and constituting a part of the machine operable to handle amounts expressed in denominations of English currency such as pounds, shillings and pence; also common fractions such as twelfths, sixteenths, etc.; feet and inches; hours and minutes; degrees and minutes; bushels and pounds; and various other mathematical computations.

The drawings illustrate one form of the invention embodied in a Dalton adding machine. In the specific embodiment illustrated the machine is adapted for handling of English currency including pounds, shillings and pence. According to the English system of currency twelve pence make one shilling, and twenty shillings make one pound. While in this particular embodiment of the invention illustrated only the recording mechanism of the two lower numerical orders are modified. It is obvious that the same or other modifications necessary to perform other or similar examples of computation could be extended to any other orders in the machine, in which case the machine would be provided with differential mechanism in which the numbers would be set up according to the decimal system of notation and the sums when added would be recorded or made to appear according to the duodecimal system of notation. A single character would in that case be employed for 10 and also another character for 11, just as for the digits 1 to 9.

In the drawings, in which I have illustrated the present invention,

Figure 1 is a side elevation of the operating mechanism, the case of the machine

and certain of the shafts and other parts thereof being in section.

Fig. 2 is a view illustrating the type-carrier and some of its associated parts which coöperate with stops in one or two numerical orders in the differential mechanism as required to record and add one or more digits at a single operation.

Fig. 3 is a rear elevation of the recording 10 type-carriers and the associated racks which coöperate with the adding wheels or pinions.

Fig. 4 illustrates in detached relation two 15 coöoperating members which coöperate with the type-carrier that is operable to record one or more digits at a single operation.

Fig. 5 is a sectional view on a line 5—5 of Fig. 1.

Fig. 6 is a detail view illustrating in rear 20 elevation the controlling members which co-operate with the stops in two numerical orders in the differential mechanism to enable the digits set up in said two orders to be recorded by operation of a single type-carrier. Some of the parts have been 25 omitted for the sake of clearness.

Fig. 7 is an inverted view illustrating the two pinions and racks constituting a part of the mechanism shown in Fig. 6.

Fig. 8 is a detail view showing some of 30 the controlling mechanism that was omitted from Fig. 6.

Fig. 9 is an enlarged view of the adding 35 pinion or wheel in the tens of shillings order by which carrying or transferring to the next higher order, that is to the units of pounds order, is caused every time the tens of shillings wheel moves two spaces or teeth.

As previously stated, my present invention 40 is shown embodied in an adding machine which includes many of the elements and mechanisms disclosed in Hopkins' Patent No. 1,039,130. The adding machine of that patent is well known commercially as 45 the Dalton adding machine. The Dalton adding machine which is manufactured under the Hopkins patent mentioned includes a series of ten numeral keys 1 conveniently arranged in a key board and mounted upon 50 levers 2 which are pivoted upon a support 3. The levers 2 converge at their rear or inner extremities and all but that for the figure 9 are provided with hammers or extended portions 4 formed in a row at right 55 angles to the rows of keys in the key board.

The hammers or extensions 4 are arranged to act upon differential stop pins 5 supported by a transversely movable frame or carriage 6 having rollers 7 operating upon 60 transverse rails 8. The digits of the numbers are set in the differential mechanism by operation of the keys and as an incident thereto the carriage and the stops therein are moved laterally from order to order to 65 position the stops to limit movement of the

type-carriers and their associated racks which operate the pinions or wheels. As in the Dalton adding machine and the machine of the Hopkins patent, the type-carriers and racks are pivotally suspended from 70 a shaft 9. Each of the type-carriers is co-operatively related to a hammer 10 normally held by releasable latches 11 from which they are independently releasable as an incident to operation of corresponding type-carriers to recording position. The type-carriers and racks are normally held in retracted positions by a transverse rod 12 supported cross wise in front of the depending portions of the type-carriers and racks by 80 arms 13 carried by the shaft 9.

After any number has been set in the differential mechanism the arms 13 are swung forwardly to carry the rod 12 out of contact with the type-carriers and racks, which are 85 thereupon actuated by springs 14 until stopped by engagement with the differential stops 5 in the usual manner.

The adding mechanism of the Dalton adding machine and the machine of the Hopkins patent mentioned, comprises a series 90 of adding pinions or wheels 15 (Fig. 5) independently revolubly mounted upon a shaft supported by a swinging frame 16. The adding pinions or wheels are movable by 95 oscillation of the frame 16 into and out of mesh with the racks 17 coöperatively associated with the type-carriers so that, as an incident to the operation of said type-carriers to record the numbers set up in the 100 differential mechanism, the adding pinions or wheels will be operated to add the numbers. In the usual decimal system of notation the racks and pinions are automatically 105 operable to carry or transfer from lower 110 to higher numerical orders in the series when the total value of the digits introduced into any of the wheels or pinions by successive 115 operations thereof amounts to ten for each numerical order. Thus, when the pinion or wheel in units order has been set to indicate nine for instance, and another digit is added thereto, the units pinion or wheel is operated to or beyond the decimal position and as an incident thereto the rack in tens order 115 is caused to actuate the pinion or wheel in tens order one space, to correspond to the digit which has been carried or transferred over from units to tens order. This operation is quite familiar and will be readily understood without extended description.

It is in association and coöperation with the above described mechanisms of the Dalton adding machine that I have chosen to illustrate the preferred embodiment of my 125 present invention. In the present instance I have illustrated my invention adapted for the addition of English currency with the provision that there shall be a single numerical order of the recording mechanism 130

for recording pence; that the next two higher numerical orders of the recording mechanism shall be operative for recording shillings, and the remaining higher numerical orders of the recording mechanism shall be operative for recording pounds; and with the further provision for automatically effecting the transferring or translation of pence to shillings, and shillings to pounds, 10 in accordance with the English currency system. Thus, when the total of pence added in the machine equals or exceeds twelve pence transferring is automatically effected into the units order of shillings, 15 since, according to the English currency system, twelve pence make one shilling. So, also, when the total of shillings added in the machine equals or exceeds twenty shillings transferring is automatically effected 20 into the units order of pounds, since, according to the English currency system, twenty shillings make one pound. It will be understood, of course, that the system of transferring from lower to higher orders may 25 readily be varied for the addition and translation into their higher equivalents of inches to feet, minutes to hours, minutes to degrees, pounds to bushels, and other examples of that general class without materially 30 or in principle varying or departing from the embodiment of my invention illustrated.

As previously stated, I prefer to employ a single type-carrier for recording the number of pence. In the form shown the type-carrier 18 is of the same general shape and configuration as the type-carriers of the usual Dalton adding machine, except that said carrier supports a rack 19 adapted to cooperate with a specially constructed pinion 20 independently revoluble upon the same shaft with the pinions 15. The pinion 20 in the machine for addition of English currency is the pinion for the addition of pence and is therefore formed with twelve teeth, so that at each complete revolution of said pinion 20 carrying or transferring will be effected into the units of shillings order in the same way that carrying or transferring is attained in the adding machines previously mentioned. The type-carrier 18 is further formed with a rack 21 which is in constant mesh with a small pinion 22 revolvably mounted upon a supporting stud 23 in rigid connection with a larger pinion 24. The two pinions 22 and 24 constitute a part of the controlling mechanism whereby the single type-carrier 18 is controlled by the differential mechanism to record the pence items. Thus, on some occasions it is necessary to record an item of 1, 2, 3 or 4 pence, for instance, and on other occasions it is necessary to record items of 10 or 11 pence, for instance. In the latter case the single type-carrier 18 must necessarily operate to record the two digits indi-

cating the number of pence, and said two digits are indicated by stops 5 in two different numerical orders in the differential mechanism. This necessitates the provision of devices for coöperating with the stops in the two different numerical orders in the differential mechanism at the same time in order that the type-carrier 18 may be operated to record 10 or 11 pence as may be required. For the recording of the pence the type-carrier 18 is equipped with twelve movable type 25 arranged in sequential order from a type for printing zero at the top to a type for printing eleven at the lower end of the series. In the Dalton adding machine and the machine of the Hubert Hopkins patent hereinbefore referred to the type-carrying sectors stand with the "0" type slightly below printing position. The type-carrier 18 is so arranged that its "0" type stands in printing position when the type-carrier 18 is in its idle position. The rack 19 associated with the type-carrier 18 is never required to operate in the carrying or transfer of the tens, as there is no lower order from which carrying could be necessary. No necessity therefore exists for the extra movement away from printing position usually found in the Dalton machine. This extra movement is provided for in the present instance in the case of all the remaining type-carriers.

I will now describe the mechanism under control of the differential mechanism for governing and controlling the type-carrier 18 in its recording and adding operations to record and introduce into the adding pinion 20 at a single operation any digit or number from one to eleven inclusive. While each of the type-carriers other than the type-carrier 18 has a projecting part 26 (Fig. 3) for engagement with the differential stops to limit movement of the type-carriers and racks, it will be observed by reference to Fig. 2, that the type-carrier 18 does not have any projection corresponding to the projection 26; and as a result of this construction, the type-carrier 18 must be controlled and limited in its movements otherwise than by such a projection. A rack member 27 is suspended from the shaft 9 in a position corresponding to the next lower numerical order from the type-carrier 18, and is in constant mesh with the pinion 24. As previously stated, the pinion 24 is in rigid connection with the pinion 22 so that both of said pinions revolve together; and the pinion 22 is in permanent mesh with the rack 19 constituting an integral part of the type-carrier 18. In the particular embodiment of my invention illustrated, which is for the addition of English currency, the pitch line of the pinion 22 is to the pitch line of the pinion 24 approximately as ten is to twelve; or, expressed in another

manner, the pinion 22 may contain ten teeth while the pinion 24 has twelve teeth. These two pinions being rigidly united and revolvably mounted upon the stud or shaft 23, it is 5 obvious that when the rack 27 moves, the rack 19 and the type-carrier 18 will also move in the same direction, but at a less rate of speed or ratio of movement, being as twelve (for the rack 27) is to ten (for 10 the rack 19 and type-carrier 18).

The rack 27 has a projection 28 extending toward the right relative to the operator facing the machine, and projecting through an arcuate slot 29 in a member 30 suspended 15 from the shaft 9 and spaced slightly from the rack 27 in order to obviate frictional contact of the parts. The rack 27 has a rearward extension 31, and a retractile spring 34 (Figs. 1 and 2) connects the said 20 arm 31 with a stationary part 35 and is thereby effective to actuate both the rack 27 and the part 30 forwardly when the projection 28 reaches the forward end of the slot 29. As previously stated, the entrained 25 connection of the rack 27 with the type-carrier 18, through the pinions 24 and 22 and the rack 21 results in moving the type-carrier 18 relative to the rack 27 in the proportion of ten spaces or teeth for each 30 twelve spaces or teeth through which the rack 27 moves. A pawl 36 is pivoted to the part 30 at 37 and has a hook on its forward end normally engaging in front of the projection 28 thereby latching the rack 27 with 35 the part 30. A spring 38 connecting the pawl 36 with the part 30 yieldingly retains the pawl in latching position and prevents independent movement of the rack 27 relative to the part 30, except when 10 pence or 40 11 pence are set up in the differential mechanism and the machine is operated to record such item and to introduce it into the adding pinion 20. When the pawl 36 is disengaged from the projection 28, movement of the 45 pawl by the spring 38 is limited by an abutment 39 so that when the projection 28 is pressed against the oblique forward end of the pawl 36, the latter will be pressed downwardly to permit the pawl to pass to 50 the rear end of the slot 29 and again be engaged by the pawl. The part 30 is provided with a projection 40 adapted to engage with one of the differential parts 5 in units numerical order and thus limit movement of the 55 part 30. Since movement of the rack 27 and the part 30 is permitted when any one of the differential stops is set to represent units of pence, it will be understood that said parts are movable to different positions 60 corresponding to any of the digits representing units of pence from 1 to 9 inclusive, and that the type-carrier 18 and rack 19 move coördinately therewith at less rate of speed and to less extent in order to carry 65 out the proper ratio of differential move-

ment between said parts. However, whenever either 10 pence or 11 pence have been set up in the differential mechanism (and, of course, no greater number of pence is ever set up in the differential mechanism at one 70 time) one of the stops in the differential mechanism is set in tens numerical order and one of said stops is set in units numerical order. It is necessary, therefore, to provide means for controlling the type-carrier 75 18 to enable it to move ten spaces or eleven spaces as the case may be, under control of the two stops in units and tens numerical orders, so that at one operation of the type-carrier the item of 10 pence or 11 pence will 80 be recorded and introduced into the adding pinion 20. This necessitates the provision of means for coöperating with the two stops representing pence in units and tens numerical orders, so that the type-carrier will be 85 properly controlled to record that item and to introduce it into the adding pinion. I will now describe the means for attaining that control.

An arm 41 is pivoted upon the shaft 9 90 between the type-carrier 18 and the rack 27 and is provided on its lower end with a forward projection 42 in vertical alinement with the rack 19 and spaced in the next higher numerical order from the projection 95 40. That is to say, the projections 26 on the usual type-carriers and the projections 40 and 42 are equi-distantly spaced in conformity with the rows of differential stops 5 in the carriage 6, so that when the stops 100 are set in units, tens, hundreds and thousands numerical orders, for instance, in the differential mechanism, the projection 40 will engage the stop in units numerical order, the projection 42 will engage the stop 105 in tens numerical order and the next adjacent projections 26 will engage the stops in hundreds and thousands numerical orders, respectively. The arm 41 also has a rearward projection 43 having a pin 44 engaging in a slot 45 in a bell crank lever 46 pivotally mounted upon a shaft 47 supported by the frame of the machine rearwardly from the type-carriers and racks. A retractile spring 48 connects the forward arm of 110 the bell crank lever 46 with a rod 49 supported by the arm 41 and normally abutting against the arms 13 and thereby holding the projection 42 rearwardly out of the path of movement of any of the differential stops 115 120 while they are being moved transversely of their proper numerical orders by the carriage 6. The pin 50 on the forward arm of the bell crank lever 46 with which the spring 48 is connected, extends under the tail of 125 the pawl 36, so that when the lower end of the arm 41 moves forwardly to engage the "1" stop in tens numerical order, the said pin 50 will be raised by contraction of the spring 48 and thus disengage or unhook the 130

- pawl 36 from the projection 28, and thus enable the spring 34 to actuate the rack 27 forwardly the full length of the slot 29, or until the projection 28 contacts with the forward wall of said slot. This movement is equivalent to a distance of ten teeth on the rack 19, so that said rack 19 and the type-carrier 18 will thereby be moved forwardly in accompaniment with the movement of 10 the rack 27 a distance of ten teeth, thus positioning the "10" type of the series of type 25 at the printing line in position to be driven to print by the hammer 10 cooperatively related to the type-carrier 18.
- 15 Through the usual controlling mechanism of the Dalton adding machine, as disclosed in the Hopkins patent and other patents, adding pinions or wheels are disengaged from the racks during forward movement 20 of the type-carriers and are automatically engaged with the racks throughout their return movement, so that the numbers recorded will be introduced into the adding mechanism. Therefore, when the type-carrier 18 25 is operated in the manner described to record the item of 10 pence, the adding pinion 20 will be operated on the return or rearward movement of the type-carrier 18 and its connected rack 19, and thereby set to 30 represent the item of 10 pence or add the same to any other item of pence previously introduced into the adding pinion 20.
- If it be required to record or add the item of 11 pence, in addition to setting the "1" 35 stop in tens of pence order, there would be another "1" stop set in the units of pence order and, when the controlling mechanism of the machine is operated, the part 30 will be moved forwardly to engage the projection 40 with the "1" stop in units order. Obviously, this will enable the rack 27 to move a corresponding additional distance forwardly, thereby also actuating the type-carrier 18 and its connected rack 19 an 45 equivalent proportionate distance in order to present the "11" type on said type-carrier at the recording line. On the return movement of the type-carrier the adding pinion 20 will be turned or set to represent 11 pence, 50 or said item will be added to any other item of pence represented in said pinion, and transferring to the next higher order, which is the units order of shillings, is effected in the usual manner. As is well known transferring from a lower to a higher order in a machine of the Dalton type is effected by movement of the rack in the higher order to which the transfer is made. Such movement occurs when the latch for the rack in 55 the higher order is tripped by the adding pinion in the order from which the transfer is made. In the present instance the pinion 20 controls the latch for the units of shillings pinion just as in the usual Dalton machine so that at each complete revolution of 60 the pinion 20 transfer is made to the units of shillings pinion. When 9 pence or less are to be recorded and added the "0" stop is set in the tens of pence order and this stop prevents movement of the arm 41 as a consequence of which the pawl 36 is not released from the projection 28. It is therefore seen that values not exceeding 9 pence are introduced into the adding pinion by the forward movement of the rack 27 while it remains 65 latched with the part 30, said rack 27 actuating with it the type-carrier 18 and the rack 19.
- 70 Since, according to the British system of currency, twenty shillings make one pound, 80 it is necessary to carry or transfer from the tens of shillings order to the units of pounds order whenever the total of shillings equals or exceeds twenty. This necessitates carrying or transferring from tens of shillings to 85 units of pounds order by each alternate tooth on the adding pinion in the tens of shillings order. For this purpose the tens of shillings pinion illustrated in detail in 90 Fig. 9 is provided with a tripping or carrying lug 51 on each alternate tooth which operate to effect carrying or transferring to the next higher order that is, to the units of pounds order, in precisely the same manner that the usual carrying lugs operate to effect 95 carrying or transferring in the orders heretofore mentioned.
- 95 In amounts like £153 6s 9d if a "0" is not desired before the "6" in shillings and the "9" in pence provision may be made in a 100 well understood way for properly "splitting" the machine to interrupt the automatic printing of ciphers at these two places.
- I claim:
1. An adding machine, comprising differential mechanism, adding pinions, racks for operating the adding pinions to add the items set up in the differential mechanism, and means for limiting movement of the racks by the differential mechanism, one of 105 said racks being arranged to cooperate simultaneously with a plurality of orders in the differential mechanism and to operate one of said adding pinions to position to represent a number composed of a plurality of 110 digits set up in a plurality of orders in the differential mechanism.
  2. An adding machine, comprising differential mechanism corresponding to a plurality of numerical orders, adding pinions 115 for adding items set up in the differential mechanism, racks controlled by the differential mechanism for operating the adding pinions in adding operations, an additional adding pinion settable in positions to represent one or more digits in the process of addition as required by the nature of the work being performed by the machine, a rack for 120 operating the additional adding pinion, and means for causing said last-named rack to 125

introduce into said additional pinion at one operation an item composed of one or more digits set up in the differential mechanism and intended to be introduced into said additional pinion.

3. An adding machine, comprising differential mechanism corresponding to a number of numerical orders and arranged to have the digits of numbers set up therein according to the decimal system of notation in which ten units of one order make one unit of the next higher numerical order; adding pinions for adding the numbers set up in the differential mechanism; racks controlled by the differential mechanism for operating the adding pinions to introduce therein the items set up in the differential mechanism, certain of said racks being arranged to operate the corresponding adding pinions to add and to transfer from lower to higher orders according to the decimal system of notation, and another rack being arranged to operate the corresponding adding pinion to transfer thereto only when more than ten units are added in the pinion from which transferring is effected; and means for controlling the rack corresponding to the last-named pinion by parts of the differential mechanism in a plurality of orders whereby the last-named rack will introduce into the corresponding adding pinion at a single operation a number consisting of a plurality of digits set up in adjacent orders in the differential mechanism.

4. An adding machine, comprising differential mechanism corresponding to a number of numerical orders and arranged to have the digits of numbers set up therein, adding pinions for adding numbers set up in the differential mechanism, an actuator for one of said adding pinions, and means for controlling said actuator to introduce into the adding pinion operated thereby at a single operation the digits set up in a plurality of numerical orders in the differential mechanism.

5. An adding machine, comprising differential mechanism including stops settable in different numerical orders to represent the digits of numbers, adding pinions for adding the numbers set up in the differential mechanism and racks controlled by the differential mechanism for operating the adding pinions in adding and transferring operations to add the numbers set up in the differential mechanism, one of the racks being arranged to coöperate simultaneously with stops in a plurality of numerical orders in the differential mechanism.

6. An adding machine, comprising differential mechanism including stops settable in different numerical orders to represent the digits of numbers to be added, adding pinions for adding the numbers set up in the differential mechanism, racks controlled by

the differential mechanism for operating the adding pinions to add the numbers set up in the differential mechanism, one of the racks being arranged to coöperate simultaneously with stops in a plurality of orders in the differential mechanism and with one of said adding pinions, and a type-carrier coöperating with that one rack for recording the digits represented in the differential mechanism with which said rack coöperates.

7. An adding machine, comprising differential stops settable in different numerical orders to represent the digits of numbers, adding pinions, racks controlled by the differential stops, and means for causing one of the racks to introduce into one of said adding pinions at one operation an item composed of a number of digits represented by stops in the different numerical orders.

8. An adding machine, comprising differential stops settable in different numerical orders to represent the digits of numbers, adding pinions, racks controlled by the differential stops, means for causing one of the racks to introduce into one of said adding pinions at one operation an item composed of a number of digits represented by stops in the different numerical orders, and a recording device coöperating with that one rack for recording at the same operation therewith the number introduced into the adding pinion.

9. An adding machine, comprising differential mechanism arranged in a plurality of numerical orders, adding pinions, racks controlled by the differential mechanism for actuating the adding pinions, means whereby one of said racks will operate a single one of the adding pinions to introduce therein at one operation a number composed of a plurality of digits set up in the differential mechanism, a type-carrier coöperating with the last named rack, type on said type-carrier, and means coöperating with said type-carrier and type to print at the same operation with said rack the plurality of digits introduced by said rack into said adding pinion.

10. An adding machine, comprising differential mechanism including stops settable in different numerical orders, adding pinions, racks controlled by the differential mechanism, means for controlling one of said racks in each operation thereof by stops in a plurality of numerical orders and causing said rack to operate a single one of the adding pinions, and a recording device coöperating with that one rack for recording the digits introduced by said one rack into said single one of the adding pinions.

11. An adding machine, comprising differential mechanism including stops settable in different numerical orders to represent the digits of numbers, in combination with an actuator controlled in each operation

- thereof by stops in a plurality of numerical orders, and a single adding pinion under control of said actuator and settable thereby to represent the plurality of digits represented by the stops in the differential mechanism controlling said actuator.
12. An adding machine, comprising differential mechanism including stops settable in different numerical orders to represent the digits of numbers, in combination with an actuator controlled in each operation thereof by stops in a plurality of numerical orders, a single adding pinion under control of said actuator and settable thereby to represent the plurality of digits represented by the stops in the differential mechanism controlling said actuator, and a recorder for recording at the same operation the plurality of digits aforesaid.
13. An adding machine, comprising differential mechanism, adding pinions, a rack for operating one of said adding pinions, means for coöperating said rack and the differential mechanism to introduce into the adding pinion operated thereby at a single operation the digits set up in a plurality of orders in the differential mechanism, and a recorder coöperating with said rack for recording said digits.
14. In an adding machine, an adding pinion, a rack for operating said adding pinion, a type-carrier in connection with said rack, an additional rack in connection with said type-carrier, a controlling pinion meshing with said additional rack, means for actuating said type-carrier and said racks to different selected positions, and means coöperating with said controlling pinion to stop said type-carrier and said racks in their different selected positions.
15. In an adding machine, an adding pinion, a rack for operating said adding pinion, a type-carrier in connection with said rack, an additional rack in connection with said type-carrier, a controlling pinion meshing with said additional rack, means for actuating said type-carrier and said racks to different selected positions, stops, and means coöperating with said stops for stopping rotation of said controlling pinion as required to stop said type-carrier and said racks in their different selected positions.
16. In an adding machine, an adding pinion, a rack for operating said adding pinion, an additional rack in connection with said first-named rack, a controlling pinion meshing with said additional rack, means for operating said racks as required to actuate said adding pinion in adding operations, and means for stopping said controlling pinion after rotation to any desired extent to limit movement of said racks.
17. In an adding machine, an adding pinion, a rack for actuating said adding pinion in adding operations, an additional rack in connection with said first-named rack, a controlling pinion permanently meshing with said additional rack, a spring actuated connection for actuating said racks in one direction, mechanism coöperating with said controlling pinion to stop movement of said racks in the direction aforesaid, and a device for actuating said racks to their starting points as required to actuate said adding pinion in adding operations.
18. In an adding machine, an adding pinion, a rack for operating said adding pinion, a controlling pinion for limiting movement of said rack in one direction, stops, movable devices under control of said stops, and means whereby said movable devices control and limit rotation of said controlling pinion.
19. In an adding machine, an adding pinion, a rack for actuating said adding pinion, a controlling pinion for limiting movement of said rack, an additional pinion in connection with said controlling pinion, and means coöperating with said additional pinion to stop rotation of said controlling pinion and thereby stop movement of said rack in different selected positions.
20. In an adding machine, an adding pinion, a rack for actuating said adding pinion, a controlling pinion for controlling said rack, an additional pinion in connection with said controlling pinion, a rack for limiting rotation of said controlling pinion, and differential mechanism controlling said last-named rack.
21. In an adding machine, an adding pinion, a rack for operating said adding pinion in adding operations, a controlling pinion for limiting movement of said rack in one direction, an additional pinion in connection with said controlling pinion, a controlling rack meshing with said additional pinion, a device for stopping movement of said controlling rack, and differential mechanism controlling said device.
22. In an adding machine, an adding pinion, a rack for operating said adding pinion, a controlling pinion for limiting movement of said rack in one direction, a controlling rack for stopping rotation of said controlling pinion, a device for stopping movement of said controlling rack, a connection between said device and said controlling rack, and differential mechanism for stopping movement of said device in different selected positions.
23. In an adding machine, an adding pinion, a rack for operating said adding pinion, an additional rack in connection with said first-named rack, a pinion meshing with said additional rack for stopping movement of said racks in one direction, means for actuating said racks, devices for limiting movement of said controlling pinion, and differential mechanism controlling said devices.

24. In an adding machine, an adding pinion, a rack for operating said adding pinion, an additional rack in connection with said first-named rack, a controlling pinion for limiting movement of said additional rack, a rack governing said controlling pinion, and differential mechanism for stopping movement of said last-named rack.

25. In an adding machine, the combination with an adding pinion, a rack for operating said adding pinion, and a controlling pinion for controlling said rack and limiting extent of movement thereof, of differential mechanism, an additional pinion in connection with said controlling device, and means coöperating with said differential mechanism and said additional pinion to determine extent of movement of said controlling pinion and to stop movements of said controlling pinion and thereby said rack in different selected positions.

26. In an adding machine, an adding pinion, a rack for operating said adding pinion, a device for limiting extent of movement of said rack, a releasable latch connecting said rack with said device, differential stops settable to stop said device and thereby said rack in different selected positions, means for moving said rack to the different selected positions, a releasable connection between said device and said rack whereby they are held together for concurrent movement, and means for releasing said connection to enable said rack to move independently of said device.

27. In an adding machine, an adding pinion, a rack for operating said adding pinion, a controlling device for said rack, a member for stopping said controlling device and thereby said rack, an element arranged to coöperate with said controlling device to stop the same, a connection between said controlling device and said element whereby they may be moved together, and means for disconnecting said connection to enable said controlling device to move independently of said element.

28. In an adding machine, an adding pinion, a rack for operating said adding pinion, a controlling device for said rack, a member for controlling said controlling device, an element for stopping said member, a latch connection whereby said element and said member will be held together in operation, and means for releasing said latch connection and enabling said member to be operated independently of said element.

29. In an adding machine, an adding pinion, a rack for operating said adding pinion in adding and clearing operations and controlled by said adding pinion in clearing operations, a controlling device for controlling said rack in adding operations, a member for controlling said controlling device in adding operations, an element limiting

movement of said member in adding operations, and means for operating said member and said rack independently of said element in clearing operations.

30. In an adding machine, an adding pinion, a type-carrier operable in recording operations, a rack operated by said type-carrier in adding and clearing operations, a controlling device for said rack in adding operations, a member for controlling said controlling device and thereby said type-carrier and said rack in recording and adding operations, an element for limiting movement of said member in certain adding operations, and means for operating said member and said type-carrier and rack independently of said element in operations to clear said adding pinion and to record the total represented therein.

31. In an adding machine, an adding pinion, a type-carrier operable in recording operations, means whereby said type-carrier will operate said pinion in adding and in clearing operations, a controlling device for controlling said type-carrier in adding operations, a member for controlling said controlling device in adding operations, an element coöperating with said member in certain adding operations, said member operating independently of said element in certain other adding operations and in clearing operations, and means for limiting movement of said element.

32. In an adding machine, an adding pinion settable to represent a plurality of digits at a single operation, a type-carrier operable in recording operations to record a plurality of digits at a single operation corresponding to the digits represented in said adding pinion, stops arranged in numerical orders, and mechanism for controlling the operation of said type-carrier in any selected operation thereof by stops set in a plurality of numerical orders.

33. In an adding machine, an adding pinion, a rack for operating said adding pinion, a recording instrumentality for operating said rack, a controlling device for the recording instrumentality, a pinion in connection with said controlling device for limiting movement of the same, a rack meshing with said pinion, an element for limiting movement of said rack, a releasable latch connecting said element and said rack, and means for releasing said latch to enable said rack to move independently of said element.

34. In an adding machine, an adding pinion, a rack for operating said adding pinion, an additional rack in connection with said first-named rack, a controlling pinion meshing with said additional rack, an additional pinion in connection with said controlling pinion, a rack meshing with said additional pinion, an element for controlling movement of said last-named rack, a releasable latch

between said element and said last-named rack, means for releasing said latch to enable said last-named rack to be operated independently of said element, and means for 5 reëngaging said latch to cause said element and said last-named rack to be operated together.

35. In an adding machine, a type-carrier movable to and from recording positions, 10 differential mechanism, a movable element controlled by the differential mechanism, a rack in connection with said movable element, a pinion meshing with said rack, and a rack in connection with said type-carrier 15 under control of said pinion, whereby extent of movement of said type-carrier is determined by said movable element and the differential mechanism.

36. In an adding machine, differential 20 mechanism settable to represent the digits of numbers, a type-carrier movable to recording positions corresponding to the digits set in the differential mechanism, a rack in connection with said type-carrier, a pinion 25 meshing with said rack, a movable element controlled by the differential mechanism, and a rack in connection with said movable element for stopping rotation of said pinion to stop said type-carrier in recording 30 positions corresponding to the digits set in the differential mechanism.

37. In an adding machine, differential mechanism settable to represent the digits of numbers, a type-carrier movable to recording 35 positions corresponding to the digits set in the differential mechanism, a rack in connection with the type-carrier, a pinion meshing with said rack, a movable element controlled by the differential mechanism, a 40 controlling rack in connection with said movable element for controlling said pinion to stop said type-carrier in recording positions corresponding to the digits set in the differential mechanism, and means for releasing 45 said controlling rack from said element to enable said controlling rack to operate independently.

38. In an adding machine, differential mechanism settable to represent the digits 50 of numbers, type for recording the digits of the numbers set in the differential mechanism, a carrier upon which said type are mounted, a rack in connection with said type-carrier, a pinion meshing with said 55 rack, a controlling rack for limiting rotation of said pinion, and means under control of the differential mechanism for limiting movement of said controlling rack.

39. In an adding machine, a type-carrier 60 movable to and from recording positions, differential mechanism, an element controlled by the differential mechanism, a controlling rack releasably connected to said element, a rack in connection with said type-carrier, a pinion meshing with said last-

named rack and being under control of said controlling rack, whereby said type-carrier is stopped in positions corresponding to the digits set in the differential mechanism, and an adding pinion under control of said type-carrier. 70

40. In an adding machine, a type-carrier movable to and from recording positions, a rack in connection with the type-carrier, a pinion meshing with the rack, a controlling 75 rack for controlling said pinion, differential mechanism, a movable element controlled by said differential mechanism, a releasable latch connecting said controlling rack and said element, and means for releasing said 80 latch to enable said controlling rack to move independently of said element as an incident to operation of said parts after certain digits have been set in the differential mechanism.

41. In an adding machine, a type-carrier, 85 type supported by said type-carrier, means for coöperating with said type to record, a rack in connection with said type-carrier, a pinion meshing with said rack, stops, a movable element controlled by said stops, a controlling rack for controlling said pinion, a latch connecting said controlling rack and said element, means holding said latch in latched position, and means for disengaging 90 said latch to enable said controlling rack to move independently of said element. 95

42. In an adding machine, a type-carrier, recording type supported by said type-carrier, means for coöperating with said type to record as an incident to operation of said 100 type-carrier, a rack in connection with said type-carrier, a pinion meshing with said rack, stops, a movable element controlled by said stops, a controlling rack for controlling said pinion, a latch holding said controlling 105 rack and said element together for equal movement when said type-carrier is operated to record any single one of the ten digits, and means for releasing said latch to enable said controlling rack to operate independently of said element when said type-carrier is operated to record two digits at a single 110 operation.

43. In an adding machine, a type-carrier, a type on said type-carrier for each of the 115 ten digits, type blocks on said type-carrier each provided with two digits, a rack in connection with said type-carrier, a pinion meshing with said rack, stops, a movable element controlled by said stops, a controlling rack for controlling said pinion to stop said type-carrier in any selected position, a latch connecting said controlling rack and said element whereby said controlling rack and said element are operated equal distances under control of a single stop when the type-carrier is operated to position to record any one of the ten digits, and means for releasing said latch to enable said controlling rack to operate independently of 120 125 130

said element when said type-carrier is operated to position any one of said type blocks having the two type thereon for recording.

44. In an adding machine, a type-carrier, recording type supported by said type-carrier, means for coöperating with said type to record as an incident to operation of said type-carrier, a rack in connection with said type-carrier, a pinion meshing with said rack, stops, a movable element controlled by said stops, a controlling rack for controlling said pinion, a latch holding said controlling rack and said element together for equal movement when said type-carrier is operated to record any single one of the ten digits, means for releasing said latch to enable said controlling rack to operate independently of said element when said type-carrier is operated to record two digits at a single operation, and an adding pinion operated by said type-carrier.

45. In an adding machine, a type-carrier, a type on said type-carrier for each of the ten digits, type blocks on said type-carrier each provided with two digits, a rack in connection with said type-carrier, a pinion meshing with said rack, stops, a movable element controlled by said stops, a controlling rack for controlling said pinion to stop said type-carrier in any selected position, a latch connecting said controlling rack and said element whereby said controlling rack and said element are operated equal distances under control of a single stop when the type-carrier is operated to position to record any one of the ten digits, means for releasing said latch to enable said controlling rack to operate independently of said element when said type-carrier is operated to position any one of said type blocks having the two type thereon for recording, and an adding pinion operated by said type-carrier.

46. In an adding machine, a type-carrier, type blocks on said type-carrier each provided with two digits, a rack in connection with said type-carrier, a pinion meshing with said rack, stops, a movable element controlled by said stops, a controlling rack for controlling said pinion to stop said type-carrier in any selected position, a latch connecting said controlling rack and said element, and means for releasing said latch to enable said controlling rack to move to position to stop said type-carrier in position to hold any selected one of said type blocks in position to be driven to print.

47. In an adding machine, a type-carrier, type blocks on said type-carrier each provided with two digits, a rack in connection with said type-carrier, a pinion meshing with said rack, stops, a movable element controlled by said blocks, a controlling rack for controlling said pinion to stop said type-carrier in position to hold any selected one

of said type blocks in printing position, a latch connecting said controlling rack and said element, means for releasing said latch to enable said controlling rack to operate independently of said element as required to enable said type-carrier to position said type blocks in printing position, and an adding pinion operated by said type-carrier.

48. In an adding machine, an adding pinion, a type-carrier operable in recording operations, means whereby said type-carrier will operate said pinion in adding and in clearing operations, a rack in connection with said type-carrier, a pinion meshing with said rack, a controlling rack for said pinion, stops, a movable element controlled by said stops, and a releasable latch connecting said controlling rack and said element, whereby said controlling rack and said element will be operated together and will limit movement of said pinion and said type-carrier.

49. In an adding machine, stops settable in units and tens numerical orders, an adding pinion, a rack for operating said adding pinion, a controlling pinion for limiting movement of said rack in one direction, a controlling rack for controlling said pinion, a movable element whose movement is limited by a stop in units numerical order, a releasable latch connecting said controlling rack and said movable element, and a device for releasing said latch when said movable element is operated after a stop other than the zero stop has been set in tens numerical orders.

50. In an adding machine, a type-carrier, a rack in connection with said type-carrier, a pinion meshing with said rack, a controlling rack for said pinion, stops settable in units and tens numerical orders, a movable element under control of any stop that may be set in units numerical order, a releasable latch connecting said controlling rack and said element, means for holding said latch in latching position during operation of said controlling rack and said element after the zero stop has been set in tens numerical order, and means for releasing said latch as an incident to operation of said controlling rack and said element after a stop other than zero stop has been set in tens numerical order.

51. In an adding machine, a type-carrier, type blocks on said type-carrier, a controlling rack, a movable element, a releasable latch connecting said controlling rack and said element, digit stops settable in units and tens numerical orders, means for releasing said latch as an incident to operation of said controlling rack and said movable element after certain stops have been set, and a device under control of said rack for limiting movement of said type-carrier, whereby any desired type block may be positioned in position for recording.

52. In an adding machine, an adding pinion, a rack for operating said adding pinion, a pinion for limiting movement of said rack in one direction, an additional 5 pinion in engagement with said first-named pinion, a controlling rack meshing with said additional pinion, a movable element having a slot therein, a pin on said controlling rack extending through said slot, a 10 latch supported by said element engaging said pin and latching said controlling rack and said element together for uniform movement, stops settable to limit movement of said element, a device for releasing said latch, and means for controlling said releasing device whereby said latch will be permitted to remain in latching engagement with said pin in certain operations and will be released from said pin in certain other operations.
